COMMUNICATION DEVICE FOR JAILS

Application filed January 8, 1932. Serial No. 585,576.

This invention relates to communication devices for jails and the like and, among other objects, aims to provide a simple and inexpensive speaking tube attachment adapted to permit conversation between a visitor and prisoner and, at the same time, effectively prevent the passage of tools, weapons, drugs, or other contraband goods from one to the other. The idea is to provide a speaking tube installation which can easily be manufactured by using ordinary pipe fittings and having provision to be removably secured to a partition or panel without using bolts, screws or the like.

Other aims and advantages of the invention will appear in the specification, when considered in connection with the accompanying drawing, wherein:

Fig. 1 is a front elevation of a speaking tube embodying the invention and showing it applied to a partition;

Fig. 2 is a vertical sectional view taken on the line 2—2 in Fig. 1; and

Fig. 3 is a horizontal sectional view taken on the line 3—3 in Fig. 1.

Referring particularly to the drawing, the preferred form of speaking tube is shown as being applied to a partition or wall 10 which is usually made of toolproof steel having a bulletproof window 11 to permit visitors and prisoners to see each other. It will be understood that such windows are usually arranged between the prisoners' day room and what is known as a visitor's corridor in a modern jail installation. The panel of glass 11 is conveniently secured in an opening in the wall or partition by means of metal frame members 12, 13 and 14. In this instance, the glass projects on the inside of the prisoner's compartment. However, it may project on either side.

In accordance with this invention, the partition 10 has a series of perforations 15 below the window frame to provide sound passages. On the inside of the partition is secured a flared mouthpiece 16 which may be made of any suitable material. It is so arranged that the prisoner may stand next to the window and see a visitor on the opposite side while a conversation is in progress.

In this instance, a speaking tube is removably connected to the outer face of the partition 10 to provide a tortuous passage from the perforations through which the sound is conducted, thus precluding the passage of any small articles through the wall. While the speaking tube may be made of many different forms, it is here shown as comprising a series of ordinary pipe fittings secured to a substantially rectangular sheet metal plate 17 having a circular opening in which the enlarged end of a reducing elbow 18 is welded, the arrangement being such that the open end of the elbow covers the perforations in the partition when the plate 17 is secured in place. The small end of the elbow 18 is shown as being secured to one end of a return bend 19 by means of a right and left hand nipple 20 having a hexagon center 21. To the other end of the return bend is connected another reducing elbow 22 conveniently by means of an ordinary short nipple (not shown). However, both reducing elbows may be secured to the return bend in any well known manner. When the nipples are employed the elbow 22 is applied first and the elbow 18 is then assembled by rotating the nipple 21 with an ordinary wrench.

There is shown a flared mouthpiece 23 having a flange 24 surrounding and secured to the enlarged end of the elbow 18 by means of screws 25. This mouthpiece is shown as having a shouldered portion 26 to provide means for clamping a wire screen 27 between it and the end of the elbow as clearly shown in Fig. 3. The wire screen is used merely to prevent the passage of any débris into the speaking tube which would clog it up. In some instances, it may be omitted.

The bottom of the return bend is here shown as having a cleanout opening which is closed by a pipe plug 28. This plug may be removed after the speaking tube is detached from the wall to afford access to the inside of the return bend. It is contemplated, however, that the whole tube may be thoroughly cleaned by a strong jet of water.

While the speaking tube may be detachably secured to the wall in a great variety of ways, the rectangular plate 17 is here shown as

- having its upper end or edge slid beneath a sheet metal frame element 29 which is riveted or otherwise secured to the window frame element 12 and has its lower edge spaced 5 from the wall as shown in Fig. 2. In this instance, ordinary strips 30 are secured to the partition on opposite sides of the plate so that its opening will register properly with the perforations in the wall.
- 10 To prevent unauthorized removal of the speaking tube, and lock it in place, a sheet metal tongue or locking projection 31 is secured to the wall or partition 10 below the lower edge of the plate and is adapted to 15 project through an opening in a tab 32 on the lower edge of the plate directly below the plug 28. The arrangement is such that, when the plate is slipped into place against the partition, the outer end of the tongue 31 20 projects below the head of the plug so as to prevent the plug from being unscrewed. The tongue is shown as having an opening to receive the shackle of an ordinary padlock 33. This arrangement enables a keeper to 25 unlock the padlock and remove the speaking tube for cleaning purposes.

When the speaking tube is made of relatively small fittings, as shown in this example, it is sometimes desirable to secure 30 the elbows to each other to prevent them from being displaced by ordinary hammer blows. For this purpose, the elbows are shown as being secured to each other by an ordinary machine screw 34 which is so positioned that 35 it is not accessible to either communicant. Also, the elbow 22 on the visitor's side is shown as being secured at its back side to the plate 17 by an ordinary rivet 35.

From the foregoing description, it will be 40 seen that the simple speaking tube installation can easily be manufactured by using standard pipe fittings. Moreover, a device of this type may be applied to existing tool-proof partitions without requiring extensive 45 alterations, it being only necessary to provide a hole or series of small perforations in the partition and means removably to secure the speaking device to it. Demonstrations have shown that speaking tubes of this character 50 are very efficient in conducting sound and enable communicants to carry on conversations in privacy. Moreover, the tortuous tube is very effective in preventing the passage of any contraband articles from visitors 55 to prisoners. No baffle of any kind is required and no special tools are needed to remove the tube.

Obviously, the present invention is not restricted to the particular embodiment thereof 60 herein shown and described. Moreover, it is not indispensable that all the features of the invention be used conjointly, since they may be employed advantageously in various combinations and sub-combinations.

65 What is claimed is:

1. A speaking device for jails comprising, in combination, a partition wall having sound conducting perforations therein; a tortuous speaking tube having a reducing elbow providing an enlarged open end; means removably securing said speaking tube to one side of said wall with the enlarged branch of the elbow completely covering said perforations; and an enlarged mouthpiece on the other end of the speaking tube projecting outwardly from the wall adjacent to said reducing elbow.

2. A speaking device for jails comprising, in combination, a partition having a window therein and a sound conducting passage adjacent to the window; a speaking tube composed of a series of pipe fittings communicating with the passage in the partition; a plate carrying the speaking tube; and means to lock the plate on one side of the partition.

3. A speaking tube installation for jails comprising, in combination, a partition having a series of perforations therein to provide a sound conducting passage; a mouthpiece secured to one side of the partition; a tortuous speaking tube composed of a series of pipe fittings on the opposite side of the partition communicating with said sound conducting perforations; and means carrying the tube adapted to be detachably secured to the partition.

4. A speaking tube installation for jails comprising, in combination, a partition having a series of perforations therein to provide a sound conducting passage; a mouthpiece secured to one side of the partition; a tortuous speaking tube composed of a series of pipe fittings on the opposite side of the partition communicating with said sound conducting perforations; a rectangular plate carrying the tube; frame members on the partition adapted to engage said plate; and means to lock the plate on the partition.

5. A speaking tube installation for jails and the like comprising, in combination, a return bend having reducing elbows secured thereto to provide a pair of sound conducting openings extending in opposite directions; a partition having a sound conducting opening; means to secure the speaking tube to the partition so that one of the reducing elbows communicates with said sound conducting opening; a mouthpiece on the opposite side of the partition; a cleanout plug in the bottom of the elbow; a locking tongue secured to the partition; a plate secured to and carrying the tube; and means to lock the plate with respect to the locking tongue, said tongue projecting beneath the plug to prevent unauthorized removal.

6. In combination with a jail partition having sound conducting perforations, a tortuous speaking tube composed of a plurality of pipe fittings including a pair of adjacent reducing elbows having their enlarged

branches extending in opposite directions; and means removably to secure said speaking tube on one side of the partition adjacent to a window with the enlarged end of one elbow covering the sound conducting perforations.

In testimony, that I claim the foregoing as my own, I have hereto affixed my signature.

HOWARD P. MANLY.
